UNITED STATES PATENT OFFICE.

TOLBERT LANSTON, OF WASHINGTON, DISTRICT OF COLUMBIA, ASSIGNOR,
BY DIRECT AND MESNE ASSIGNMENTS, TO THE LANSTON TYPE MACHINE
COMPANY, OF SAME PLACE.

PRODUCING JUSTIFIED LINES OF TYPE.

SPECIFICATION forming part of Letters Patent No. 364,521, dated June 7, 1887.

Original application filed September 30, 1885. Serial No. 178,671. Divided and this application filed July 3, 1886. Serial No. 207,156.
(No model.)

To all whom it may concern:

Be it known that I, TOLBERT LANSTON, of Washington, in the District of Columbia, have invented certain new and useful Improvements 5 in the Art of Forming Justified Lines of Type; and I do hereby declare the following to be a full, clear, and exact description of the same, reference being had to the accompanying drawings, forming part of this specification, 10 and to the figures and letters of reference marked thereon.

While astonishing progress has been made in those branches of the art of printing which relate to the taking of impressions and to the 15 folding and delivery of the matter printed, but comparatively little practical advance has been made in that department which relates particularly to the setting up and justification of the lines from which the impressions are to 20 be made.

Type-setting machines of more or less efficiency, it is true, have been employed to assemble the types; but even where such machines have been successfully used, it has always 25 been found necessary to subject each line of composition to a process of justification involving, usually, the introduction, by suitable mechanism, or by hand, of additional spaces, or of the substitution of wide for narrow spaces, 30 and vice versa, much the same as in the case of matter set up by hand. It has also been proposed to produce solid lines of justified composition by justifying the dies or molds which produce them, and this justification is 35 performed in the ordinary manner above referred to.

My invention is a wide departure from the previous methods, and proceeds upon a principle which I believe to be radically new.

Instead of producing a line of composition 40 and then justifying it, I form my types for a given line in such manner as to cause them, when assembled, to form a complete justified line ready for printing direct or for making an impression for stereotype or electrotype purposes without further manipulation.

It is well known that in ordinary composition, where common type is used, it rarely ever happens that a series of words, uniformly

and regularly spaced, exactly fill a line of 50 given length, the rule being that a space of greater or less length is left at the end of the line which must be filled up or absorbed in the process of justification. Now, since it is apparent that in every case this unoccupied 55 space at the end of the line must bear a certain relation to the part of the line filled by the characters—or, in other words, represent a certain percentage of the combined width of such characters—it follows that if there be 50 added to the normal width of the body of each of the assembled types a percentage of increase corresponding to the percentage which said unoccupied space represents to the occupied space, the line composed of types so 65 formed will be rendered self-justifying. To illustrate this, suppose the unoccupied space in a line required to be taken up by justification represented one per cent. of the part of the line filled by type of the normal width, 70 the addition of one per cent. to the normal width of the body of each of such assembled type would cause this space to be taken up or absorbed, one per cent. addition to the width of each section or part of the assembled type 75 being equal to one per cent. of the whole aggregated width of said type.

Instead of thus adding to each type a certain percentage of the width thereof, the same result can be accomplished either by apportioning the unoccupied space in the line equally among all the types therein, and thus adding to all the types a certain uniform and definite increase in width—say a one five-hundredth of an inch to each, or by apportioning the unoccupied space in the line equally among the space-types between words contained therein by adding an equal amount of increase to the normal width of each of such space's value. 85

The improvement in the art, which I desire to 90 cover herein, consists, broadly stated, in first ascertaining the length of the proposed line of matter; secondly, ascertaining the space which would be required to be filled by justification if types of normal or standard size were employed; and, thirdly, forming a series of types for the line, the bodies of which or of some of which are varied as to width from the nor- 95

mal an amount sufficient in the aggregate to absorb the said space required to be filled by justification.

As is apparent, the gist of my invention is contained in the last step or operation above set forth.

As my present invention relates to improvements in the art rather than to specific mechanism, and as various well-known instrumentalities may be employed for carrying the invention into practice, I have not deemed it necessary to make specific mention herein of such devices, regarding a mere reference to my application No. 178,671, filed September 30, 1885, 15 (of which this is a division,) wherein is shown a competent mechanism, as sufficient.

In the accompanying drawings, Figure 1 is a fac-simile of an impression taken from type of standard dimensions and of a style known 20 as "double English," this variety of type being selected because of its large size and the resulting convenience in graphically representing the hereinafter-described modes of carrying out the invention. Fig. 2 is a diagrammatic view representing an unjustified line comprising the characters shown in Fig. 1, the types being shown in outline and on a scale of 25 2 to 1. Fig. 3 is a diagrammatic view representing the same characters illustrated in Figs. 30 1 and 2, justified according to what I term "the percentage-of-variation system." Fig. 4 is a similar view illustrating the line justified according to what I term "the system of uniform variation." Fig. 5 is a similar view 35 illustrating a modification of the system shown in Fig. 4, the variation being apportioned among the space types or quads only. Fig. 6 is a view of a portion of a form of types composed of lines produced in accordance with 40 my invention.

Similar letters and numbers in the several figures indicate corresponding parts.

For a clear conception of my invention, let the interval between the points lettered *a* and 45 *c*, Fig. 2, represent the length of the proposed line of composition assumed to be the width of the column. The interval between *a* and *b*, the space occupied by the unjustified line of 50 types of normal or standard size (shown in Fig. 1) and the interval between *b* and *c* the space to be filled by justification.

As the space between *b* and *c* represents a certain percentage of the space between *a* and *b*, it follows that if to each division of the space 55 *a b* there be added a corresponding percentage of its width the result will be the filling out of the line. It is also true that the distance from *b* to *c* bears a fixed relation to the number of divisions of the line *a b*. Hence, if to each 60 division is added its proportional part of the line *b c*, the result will be, as before, the filling out of the line.

An illustration of the application of my invention by what I term "the percentage-of-variation system" is represented diagrammatically in Fig. 3.

The space *b c*, Fig. 2, to be filled by justification is approximately ten per cent. of the space *a b*. Hence, if there be added to each subdivision of the space represented by the line 70 *a b*; or, in other words, to each of the twenty-three normal types which I have found would be contained in said space, ten per cent. of its width, the line will be filled out or justified.

In producing types which will, when associated together, exactly fill out the line *a c*, it is therefore only necessary that they be constructed of a width ten per cent. above the normal. This process has been followed in the making of Fig. 3, the types there being represented, as nearly as practicable, as increased 80 in width ten per cent. above the types shown in Fig. 2.

An illustration of the application of my invention by what I term "the system of uniform variation" is represented diagrammatically in Fig. 4. In this system, instead of forming the type composing the line of a width increased above the normal on the percentage plan, the space to be filled by justification is 90 distributed uniformly among them—that is to say, each of the types for the line is made of a width increased above the normal an amount equal to the space to be filled by justification divided by the number of type which would 95 compose the unjustified line. Thus, as represented in Fig. 4, each type is shown of a size increased above the normal types shown in Fig. 2 one twenty-third of the space between *b c*, the result being that when assembled they 100 fully occupy the line *a c*.

As is obvious, instead of distributing the increase among all the types in the line, whether by the system of uniform variation or the percentage-of-increase system, it may be apportioned among certain of them only—as, for example, among the space type or quads. An example of this is shown in Fig. 5, in which the space-types 2, 4, 6, 8, 13, 16, and 21 are each made of a width increased above the normal, as indicated in Fig. 2, one-seventh of the space *b c* to be filled by justification, the other types in the line being made of normal size.

In carrying out my invention, by whichever of the systems indicated, it should be understood that the types for each line of composition are formed with special reference to the needs of that line alone, and the several lines are associated together in forms, so that impressions may be taken from them, either for direct printing or for forming matrices for stereotype or electrotype purposes.

The variation in the widths of the types referred to herein relate solely to variations in the bodies and not to the impression-faces 125 thereof, which remain normal; and in this connection it may be stated that in the production of lines of ordinary-size type the variations are so slight as to be imperceptible to the eye, while uniformity of spacing is attained 130 in greater perfection than can be secured in ordinary hand-composition where justification

is effected by the employment of spaces or quads varying in width and unequally distributed.

The percentage-of-increase system and the system involving the variation of the space types or quads are claimed specifically in other divisional applications filed by me—*i. e.*, Nos. 207,157 and 207,158—and the lines and forms of matter produced in accordance with my invention are specifically claimed in still another divisional application, No. 207,159.

What I claim as new is—

1. The herein-described improvement in the art of producing justified lines of type, which consists in ascertaining the space in a line required to be filled by justification if types of a normal or standard size were used and then making in succession the types for the proposed line, the bodies of the desired number of said types being varied from normal as to width an amount equal in the aggregate to the ascertained space required to be filled by jus-

tification, whereby each line is formed by a continuous process from beginning to end of a succession of types specially made for it, 25 which just fill it out and which require no manipulation or disturbance whatever to effect the justification of said line.

2. The herein-described improvement in the art of forming justified lines of type, consisting 30 in first ascertaining the space which would be required to be filled by justification if types of normal size were employed; secondly, forming a series of types for the designated line, each of said types being made of a width varying from the normal in proportion to the space which would otherwise be filled by justification, and, finally, assembling the said types to form a line, substantially as described. 35

TOLBERT LANSTON.
